THERMIONIC VALVE CIRCUIT

Charles Cecil Eaglesfield, Surrey, England, assignor, by mesne assignments, to Radio Corporation of America, New York, N. Y., a corporation of Delaware

Application May 3, 1939, Serial No. 271,614
In Great Britain May 13, 1938

2 Claims. (Cl. 250—27)

This invention relates to thermionic valve circuits and has for its object to provide an improved circuit incorporating a valve which exhibits a saturation effect within the negative range of at least one of its characteristic curves, i. e. upon plotting in the usual manner the relationship between the current to an electrode (e. g. the anode) and the control-grid volts, the current is represented by a horizontal or substantially horizontal curve over a portion of that range of abscissae which represents negative control-grid potentials. A valve exhibiting a characteristic of this form is, for example, useful as a so-called amplitude filter in a television receiver for which purpose the ideal shape of characteristic would be constituted by a straight horizontal line extending in the negative direction from the zero ordinate and a sloping straight line extending from the end of the horizontal line to the abscissa.

According to the present invention the desired form of characteristic (if required, one that approaches closely to the said ideal characteristic for an amplitude filter) is obtained by utilising a valve of the type incorporating an auxiliary cathode (i. e. a secondary-emission electrode whose emission is caused to form an anode current greater than that formed by the primary emission from the cathode proper) and by placing a resistance or other appropriate impedance of suitable magnitude in the lead to the anode, in the lead to the auxiliary cathode, or in each of these leads.

In order that the invention may be more readily understood reference will now be made to the accompanying drawing, wherein:

Fig. 1 is a circuit diagram which serves to illustrate the principle of the invention;

Figs. 2 to 4 are graphs showing the results obtained with the circuit of Fig. 1.

The valve 10 shown in Fig. 1 incorporates a cathode 11, a control grid 12, a screening grid 13, an auxiliary cathode 14 and an anode 15. This valve may conveniently have the construction shown in Fig. 4 of the article by Jonker and v. Overbeck appearing in pages 150 to 156 of vol. 15 of the "Wireless Engineer." The heater for the cathode and other accessories such as earthed screens are not shown in the diagrammatic representation of the valve. Fig. 1 also shows a source of bias 16 connected between the cathode and control grid, a high tension battery 17, a resistance 18 included in the lead which connects the anode 15 to the battery, and a resistance 19 in the lead connecting the auxiliary

cathode 14 to the battery. The screen-grid 13 is shown connected to the same point of the battery as that to which resistance 19 is connected but it may have a connection to another point of the battery. 5

I have plotted characteristic curves of the above-mentioned form of valve utilising resistances 18 and 19 of 10,000 ohms each, an anode voltage of 250 volts and an auxiliary cathode voltage of 150 volts. Figs. 2 to 4 illustrate the results obtained. 10

When the resistance 18 is in the position shown but the resistance 19 is omitted the curve of anode current A_1 obtained upon variation of the source 16 (G_V) is shown by curve 20 in Fig. 2. 15 The formation of this curve may be explained as follows: When the anode potential is higher than the potential of the auxiliary cathode the secondary emission from the latter will be collected by the anode, whereas if the anode potential is reduced to a value only slightly higher than that of the auxiliary cathode most of the secondary emission will return to the auxiliary cathode. When the resistance 18 is placed in the anode lead a reduction of the negative bias on the control grid results in a reduction of anode potential due to the increase in the anode current and curve 20 accordingly shows a saturation effect at lower values of negative bias. 20

If on the other hand resistance 19 is placed as shown in Fig. 1 but resistance 18 is omitted we obtain curve 21 of Fig. 3. It will be noted that this curve shows the current A_{K1} to the auxiliary cathode as a function of the control grid bias in contradistinction to Fig. 2 in which anode current was plotted. The formation of curve 21 may be explained as follows. When the negative bias on the control grid is reduced the auxiliary cathode current ($-A_{K1}$) increases, thus increasing the voltage of the auxiliary cathode until it approaches the anode voltage. 30

If resistances 18 and 19 are used simultaneously we obtain the curve shown in Fig. 4, curve 22 showing the variation of anode current (A_1) and curve 23 the variation of auxiliary cathode current (A_{K1}). In this case the screen-grid 13 may advantageously be given a potential of 100 volts instead of being connected to the end of the resistance 19 as shown in Fig. 1. 40

It will be noted that in curve 22 the saturation portion has a slight upward slope whereas the corresponding curve 23 in Fig. 4 has a slight downward inclination in the saturation region. It will be clear that by suitably adjusting the value of resistance 18 the curve may be made hor- 50

izontal. As is obvious from a comparison of Figs. 2 and 4 the effect of inserting resistance 19 is to flatten the saturation region of the anode current curve.

5 Fig. 1 has been used to illustrate the principle of the invention and it is thought that it is unnecessary to show any input or output connections since these may be of any suitable character. The output voltage may be taken from 10 either resistance 18 or resistance 19 alone or, if a push-pull output is desired, from both these simultaneously. In the last mentioned case suitable adjustment of resistances 18 and 19 will produce a true amplitude balance of the voltages.

15 As is clear from the above explanation and from the accompanying graphs a circuit in accordance with the invention is applicable with great advantage as an amplitude filter in a television circuit.

20 What I claim is:

1. A circuit comprising an electron discharge tube provided with at least a source of primary electrons, a signal control grid, a source of secondary electrons and an anode, a circuit including a source of negative potential connected be-

tween the signal control grid and the primary electron source, means for impressing a positive potential on the anode and on the secondary electron source, and a voltage dropping resistance connected to each of said electrodes having positive potentials impressed thereon, said resistances being of such magnitude that the anode current-grid voltage and the secondary electron source current-grid voltage tube characteristics exhibit a saturation effect in the negative range thereof. 10

2. A circuit comprising an electron discharge tube provided with at least a source of primary electrons, a signal control grid, a source of secondary electrons and an anode, a circuit including a source of negative potential connected between the signal control grid and the primary electron source, means for impressing a positive potential on the anode and on the secondary electron source, and a voltage dropping resistance connected to the anode, said resistance being of 15 such magnitude that the anode current-grid voltage tube characteristic exhibits a saturation effect in the negative range thereof.
